PUMP

Victor N. Albertson and Robert V. Albertson, Minneapolis, Minn., assignors to Minnesota Automotive, Inc., Mankato, Minn., a corporation of Minnesota
Filed Sept. 4, 1962, Ser. No. 221,098
2 Claims. (Cl. 103—102)

This invention relates generally to axial flow pumps, and more particularly it relates to a jet-type submersible pump having a novel impeller or rotor construction and arrangement.

The novel axial flow pump disclosed herein is particularly adapted for use in connection with barrels and other types of tanks or containers. Generally, the axial flow pump disclosed herein comprises an elongated generally vertically disposed tubular conduit adapted to extend through an opening in the top of a container, a housing disclosed at the bottom end portion of said tubular conduit and containing the novel rotor and partition arrangement disclosed hereinafter, a drive shaft extending upwardly through said tubular conduit, and a drive motor positioned at the upper end portion of said tubular conduit.

An important object of this invention is the provision of an axial flow pump having a novel rotor and partition and baffle arrangement which is particularly designed for long life and very efficient operation.

Another object of this invention is the provision of a jet-type submersible axial flow pump which is economically constructed without a suction pipe, check valves, relief valves, gears and belts whereby to reduce service problems by the elimination of normally rapidly wearing parts.

While devices of the general character described herein have previously been known, the present invention comprehends a submersible axial flow pump which constitutes an improvement thereupon, both as to the efficiency derived from the structural differences and the simplicity of its construction, as well as the economy with which it may be manufactured.

The above and still further objects and advantages of this invention will become apparent from a consideration of the following detailed specification, appended claims and attached drawings.

Referring to the drawings, wherein like reference characters indicate like parts or elements throughout the several views:

FIG. 1 is a view in elevation showing our novel pump in its operating position on a barrel or other container;

FIG. 2 is an enlarged detailed view in axial section of our novel pump in the position shown in FIG. 1, with the upper portion thereof shown in elevation;

FIG. 3 is an enlarged view in transverse section taken on the line 3—3 of FIG. 2;

FIG. 4 is an enlarged view in transverse section taken on the line 4—4 of FIG. 2;

FIG. 5 is a view in section taken on the line 5—5 of FIG. 3; and

FIG. 6 is a view in elevation of the novel rotor disclosed herein and shown in FIGS. 2 and 4.

Referring again to the drawings, a barrel which may be any suitable tank or container, is represented by the reference numeral 1, the same comprising a cylindrical side wall 2 and top and bottom walls 3, 4. The top wall 3 of the barrel 1 is provided with an annular threaded collar 5 adapted to receive a plug or cap, not shown, and through which the axial flow pump to be described hereinafter may be inserted.

According to present practices, the structure disclosed herein comprises a drive motor, shown generally at 6.

2

The drive motor 6 is mounted on an annular base 7 having a central opening 8 therein, through which the motor shaft 9 projects in a generally vertically and downward direction. A mounting fitting, represented generally by the reference numeral 10, includes an enlarged flange portion 11 which is rigidly secured to the annular base 7, as shown particularly in FIG. 2.

The mounting fitting 10 further comprises a depending tubular portion 12 and a lateral outlet portion 13 adapted to receive an outlet conduit connector 14. An elongated tubular conduit represented generally by the numeral 15 is adapted for introduction through the barrel or other container having the liquid for pumping and is further adapted to convey the liquid or fluid upwardly to the outlet portion 13 of the mounting fitting 10. The upper end portion 16 of the tubular conduit 15 is securely fitted within the depending tubular portion 12 of the mounting fitting 10, as shown particularly in FIG. 2, and the lower end portion 17 of the tubular conduit 15 defines a diametrically reduced cylindrical surface 18 on which is received the upper end portion 19 of an elongated generally cylindrical generally vertically disposed housing, represented generally by the reference numeral 20, the same being secured thereto by means of the set screw 21. It is noted that an intermediate annular connector coupling 22 is received on the tubular conduit 15 and defines a lower threaded portion 23 for cooperative securement in the threaded collar 5 of the barrel top wall 3.

The housing 20 defines an internally threaded lower end portion 24 adapted to receive a screw threaded annular spider fitting 25. The fitting 25 defines a plurality of depending feet 26 and further defines a fluid inlet opening 27. Of course, the lower end portion 17 of the tubular conduit 15 which projects into the upper end portion 19 of the housing 20 in effect defines a fluid outlet opening for the housing 20. As shown particularly in FIG. 2, the housing 20 further defines a generally cylindrical chamber 28 which communicates with the fluid inlet and outlet openings of the housing 20 and is adapted for the generally axially upward flow of fluid therethrough.

The novel pumping arrangement provided by this invention comprises a pair or a plurality of generally annular partition members, each represented generally by the reference numeral 29. The partition members 29 are disposed within the chamber 28 of the housing 20 in vertically spaced relationship with respect to one another, as shown particularly in FIG. 2. The partition members 29 may be suitably formed from Teflon or other suitable material, and each thereof comprises a cylindrical wall portion 30, a plurality of generally circumferentially spaced generally radially extending fins 31, a central conical portion 32, and an intermediate flange portion 33. The fins 31 of each of the partition members 29 cooperate to define a plurality of generally axially extending fluid passages, and the fins 31 each comprise a generally axially extending upper portion 34 and a generally circumferentially extending lower angle portion 35, as shown particularly in FIG. 5. The lower angle portions 35 of the fins 31 are formed so as to extend in a generally circumferential direction which is opposite to the direction of rotation of the rotors of the pump to be described hereinafter. It is noted that below the position of the fins 31, the central conical portion 32, and the intermediate flange portion 33, each of the position members 29 defines a downwardly opening cavity, as shown particularly in FIG. 2.

In accordance with this invention, a plurality of rotors, each represented generally by the reference numeral 36, are disposed within the chamber 28 of the housing 20. Each of the rotors 36 is associated with a different one of

the partition members 29 and is received within the downwardly opening cavity defined thereby, the relative positions thereof being shown particularly in FIG. 2. As shown in FIGS. 4 and 6, each of the rotors 36 comprises an upwardly projecting central bearing portion 37, an intermediate annular flange portion 38, and a plurality of depending generally circumferentially spaced fluid-impelling vanes 39. It is noted that the vanes 39 of each of the rotors 36 are positioned angularly with respect to the radius so as to define a plurality of fluid passages 40 which also extend angularly with respect to the radii in a direction generally opposite to the intended direction of rotation for the rotor 36. The rotors 36 are adapted upon rotation thereof to move fluid from the inlet opening of the housing 20 upwardly through the passages of the partition members 29 toward the outlet opening of the housing and upwardly through the tubular conduit 15, the general path of flow being shown by arrows in FIG. 2. As shown particularly in FIGS. 2 and 4, the vanes 39 of each of the rotors 36 are radially outwardly positioned so as to define a generally centrally disposed downwardly opening recess 41. As shown particularly in FIG. 2, the partition members 29, and their associated rotors 36, are separated by an annular baffle 42, and the baffles 42 are each therefor positioned adjacent the inflow end of a different one of the rotors 36 in generally axial alignment with the vanes 39 thereof and are adapted to direct the flow of fluid into the central recess 41 defined by the associated rotor 36 positioned thereabove. The particular arrangement of the partition members 29, rotors 36, and annular baffle 42 is shown in FIG. 2, and it is noted that the uppermost partition member 29 has its upper annular edge portion disposed in engagement with an inner annular abutment 43 defined by the housing 20. The remainder of the partition members 29 and the peripheral edge portions of the annular baffles 42 are alternately positioned in engagement with one another, and a ring washer 44 and a filter screen 45 are contained within the bottom of the housing chamber 28 and secured therein by means of the screw threaded spider fitting 25.

In order to provide means for mounting the rotors 36 for rotation within the housing chamber 28, an elongated vertically disposed drive shaft 46 has its upper end portion coupled by means of a connector 47 to the depending motor shaft 9. The rotors 36 are secured on vertically spaced detented portions of the drive shaft 46, as shown in FIG. 2. As shown in FIG. 2, ball bearing and seal means 48 is provided adjacent the upper end portion of the drive shaft 46. Also, an intermediate bearing element 49 is provided adjacent the lower end portion of the tubular conduit 15. The central bearing portions 37 of the rotors 36 are secured in vertically spaced relationship on the lower end portion of the drive shaft 46, as shown particularly in FIG. 2.

The serpentine flow of fluid within the housing 20 is represented by flow lines in FIG. 2, and a particular feature of my novel pumping arrangement concerns the form of the fins 31 of the partition members 29. As noted above, the lower angle portions 35 of the fins 31 are generally circumferentially directed in a direction opposite to the direction of rotation of the rotors 36 whereby the turbulent swirling movement of the fluid being moved by the rotors 36 tends to be terminated upon engagement by the fins 31 of the partition members 29. Furthermore, the fins 31 of the partition members 29 serve to break up the above noted swirling motion and direct the flowing liquid in an upward direction so as to increase the efficiency of flow in an upward axial direction.

This invention has been thoroughly tested and found to be completely satisfactory for the accomplishment of the above objects; and while we have shown and described

above a preferred embodiment thereof in which the principals of the present invention have been incorporated, we wish it to be specifically understood that the same may be modified without departure from the scope and spirit of the appended claims.

What we claim is:

1. In an axial flow pump,
  - (a) an elongated generally cylindrical generally vertically disposed housing, said housing having a fluid inlet opening adjacent the lower end portion thereof and a fluid outlet opening adjacent the upper end portion thereof, said housing further defining a generally cylindrical chamber communicating with said fluid inlet and outlet openings and adapted for the generally axially upward flow of fluid therethrough,
  - (b) a pair of stationary generally annular partition members disposed in vertically spaced relationship in said chamber, said partition members each defining a plurality of generally circumferentially spaced fins which cooperate to define a plurality of generally axially extending fluid passages, said fins having generally axially extending upper portions and lower angle portions which extend in a general circumferential direction from the respective upper portions,
  - (c) a pair of rotors disposed in said chamber and one each associated with a different one of said partition members, said rotors each having a plurality of generally circumferentially spaced fluid-impelling vanes adapted upon rotation to move fluid from said inlet opening through said passages of said partition members toward said outlet opening, said vanes of each of said rotors being radially outwardly positioned so as to define a generally centrally disposed recess,
  - (d) a pair of annular baffles disposed in said chamber, and one each positioned adjacent the in-flow end of a different one of said rotors in generally axial alignment with the vanes thereof and adapted to direct the flow of fluid into the central recess defined thereby,
  - (e) means mounting said rotors for rotation in said chamber in a direction opposite to the circumferential extension of the angle portions of said rotor fins, and
  - (f) power means for imparting rotation to said rotors.
2. The axial flow pump of claim 1, wherein,
  - (a) each of said stationary generally annular partition members has a cylindrical wall portion lining said chamber and,
  - (b) said annular baffles being spaced and supported adjacent their peripheries by opposed ends of said cylindrical wall portions of said partitions.
